**HOLE FORMING MECHANISM FOR
BOOKBINDING MACHINE**

John O. Whitcomb, Mechanicsburg, Pa., assignor to
Hickok Manufacturing Company, Harrisburg, Pa.,
a corporation of Pennsylvania

Filed Mar. 14, 1966, Ser. No. 534,084
5 Claims. (Cl. 77-22)

ABSTRACT OF THE DISCLOSURE

The apparatus drills holes in such articles as stenographers' notebooks for the threading of a spiral binder therethrough. Two aligned series of drills are provided with the openings of each series spaced apart a distance twice the distance of the openings in the book. An un-drilled book is fed to the first series or station and openings are drilled therein whereupon such book is advanced to the second station or series for the drilling of the remaining openings in the book while a new book is fed to the first station or series.

This invention relates to a hole forming mechanism for bookbinding machines, and has particular reference to the formation of openings in one end of looseleaf books, such as stenographers' notebooks, wherein a wire coil is spun through the openings formed with the machine.

In the making of books, such as stenographers' notebooks, it is the common practice to punch the openings for receiving the wire coil binder. This is feasible provided the thickness of the book is quite limited, it being impossible to punch openings through a book of substantial thickness. Since it is becoming more and more the common practice to make books of this type substantially thicker than can be punched, it is necessary to divide the book, for example, into two parts, punch the openings in each part of the book, then reassemble the parts of the book for the threading of the coil binders through the openings. Obviously, this clearly slows down the rate of production of the books, two or more punching operations being required, and since it is difficult to accurately punch and assemble the parts of the books, the openings sometimes are not in proper alignment with each other.

An important object of the present invention is to provide an apparatus for drilling the openings in books of the type referred to wherein books of almost any thickness can be efficiently drilled for the reception of the coil binders.

A further object is to provide such a machine wherein, because of the mechanical nature of the apparatus, openings spaced apart a distance twice the distance between the openings in the finished book, are drilled through a book at one work station, whereupon such book is moved to a second work station for the drilling of the remaining openings in a second operation, a second book being moved to the first work station so that the first openings are drilled therethrough while the remaining openings are being drilled simultaneously at the second work station, with the result that each operation of the machine discharges a completely drilled book ready for the coil binding operation.

A further object is to provide novel means for advancing the books successively to the work stations, positioning the books at such stations, clamping the books in position and then performing the drilling operations simultaneously at the two stations.

Other objects and advantages of the invention will become apparent during the course of the following de-

2

scription. In the drawings I have shown one embodiment of the invention. In this showing:

FIGURE 1 is a front elevation of the apparatus;

FIGURE 2 is an enlarged vertical sectional view on line 2-2 of FIGURE 1;

FIGURE 3 is a section taken substantially on line 3-3 of FIGURE 2;

FIGURE 4 is a similar view taken substantially on line 4-4 of FIGURE 2;

FIGURE 5 is an enlarged fragmentary elevation of the left-hand unit as viewed in FIGURE 3, comprising the first work station of the apparatus;

FIGURE 6 is an enlarged section view on line 6-6 of FIGURE 5;

FIGURE 7 is an elevation similar to FIGURE 5 showing the book clamp in operation with the drills in operative position;

FIGURE 8 is an enlarged sectional view on line 8-8 of FIGURE 7;

FIGURE 9 is a perspective view of one of the supports, and

FIGURE 10 is a section on line 10-10 of FIGURE 2.

Referring to the drawings, the numeral 10 designates the frame of the apparatus as a whole comprising vertical leg members 11 and a plurality of horizontal cross members 12. A longitudinally extending, angularly arranged support 14 extends along the machine and is supported by the front leg members 11 and a similar upper plate 15 is secured to the top horizontal frame members 16. Fixed, respectively, against the longitudinal members 14 and 15 are elongated plates 17 and 18, as shown in FIGURE 2, the members 17 being clearly shown in FIGURES 6 and 8.

Two pairs of spaced supports indicated as a whole, respectively, by the numerals 20 and 21 are connected to the longitudinal member 17, as shown in FIGURE 8. To this end, the open forward end of each such body is provided with a cast angle bolted as at 24 to the member 17. Each body 20 and 21 is bolted at its other end as at 25 to supports 26 carried by the frame members 12.

The supports of each pair 20 and 21 are further provided with cast pads 30 (FIGURE 2), and to the pads of each pair of supports 20 and 21 a supporting body 31 is bolted as at 31'. Thus, two of the supporting bodies 31 are provided as shown in FIGURE 3. The upper face of each body 31 is provided with a dovetail slot 32 (FIGURES 9 and 10) in which is slidably a dovetail 34 carried by a motor support 35 on which is bolted a motor 36 as at 37. Thus, each motor 36 and associated elements are slidably upwardly and to the left in FIGURE 2.

A main drive shaft 38 is suitably supported in bearings (not shown) mounted on the frame members 12 and is constantly rotated from any suitable power source (not shown). This drive shaft is provided with a pair of cams 40 (FIGURES 2 and 3), each having an arcuate high portion 41 each engaging a roller 42 carried by one of the dovetails 34. Each cam 40 is further provided with an arcuate low portion 42, and it will be apparent that the high portion 41 moves the motors and parts connected thereto upwardly and to the left in FIGURE 2.

The shaft 38 is further provided with a plurality of cams 45 having high and low portions 46 and 46', respectively, engageable with rollers 47 carried by levers 48 (FIGURE 2) pivotally supported by the frame of the apparatus as at 48'. The free end of each lever 48 engages the lower end of a rod 49. Two of the rods 49 are slidably in each of the supports 20, and each carries a disk 50 engaging the lower end of a spring 51 (FIGURES 2 and 4).

A plurality of plates 56 and 57 extend longitudinally of the apparatus (FIGURE 2) and are suitably secured

to end frame members thereof, and the plate 56 seats on the longitudinal member 17 and engages the upper end of each of the springs 51. Each rod 49 extends slidably through the plate 56 and carries at its upper end a clamping member 58, having a downwardly and inwardly turned portion 59 terminating in a flange 60 adapted to engage a book in a manner to be described and provided with a plurality of bushings 61 (FIGURES 6 and 8) further described below. The plate 56 has bushings 62 mounted therein in alignment with the bushings 61 for purposes to be described.

The upper end of each dovetail 34 has fixed thereto a gear housing 65 in each of which is mounted a shaft 66 carrying a plurality of worm wheels 67. Each gear housing slides with its associated dovetail 34. One end of each shaft 66 externally of the gear housing 65 is provided with a pulley 68. A belt 69 passes around this pulley and around a pulley 70 on the drive shaft of the associated motor 36.

Each gear housing 65 rotatably supports a plurality of spindles 75, each gear housing being provided with bearings 76 for this purpose. Each of the spindles carries a worm 77 meshing with one of the worm wheels 67 to be rotated thereby. Each spindle 75 carries a suitable chuck 78 of any desired type, in which is mounted the lower end of a drill 79. Each drill is in alignment with a pair of bushings 61 and 62. The drills are shown in retracted positions in FIGURES 3, 5 and 6 and are shown in operative positions in FIGURES 7 and 8.

Above the plate 56 is arranged a plate 80 (FIGURES 1 and 2) slotted as at 81 for the passage therethrough of a pair of pushers 82. Each pusher 82 is pivoted as at 82' (FIGURES 5 and 7) to an angle iron 83, one flange of each of which is movable in the groove of a plurality of rollers 84, the angle irons being tied together as at 85 (FIGURE 2). Each finger 82 has its movement limited by a stop 83' and is counterweighted as at 84' to be biased to the position shown in FIGURE 5. One of the connecting members 85 is connected to one end of a link 87, the other end of which (FIGURE 1) is connected to one end of a lever 88 pivotally supported at its other end as at 89. A connecting rod 90 is pivotally connected at one end as at 91 to the lever 88 and at its other end as at 92 to a wheel 93. This wheel is carried by a shaft 94 extending transversely of the machine and having a beveled gear 95 meshing with a similar gear 96 carried by the main drive shaft 38.

Thus, the angle irons 83 and pushers 82 are reciprocated once during each revolution of the wheel 93. Pairs of these pushers are shown in FIGURE 1. The two pairs to the right receive therebetween a book placed manually on the plate 80 by an operator, the lower edge of the book being slidably supported by a flanged guide 98. The book thus placed in position will be moved at the proper time to the same position or work station now occupied in FIGURE 1 by the two left-hand pairs of pushers 82, a book between the latter pairs of pushers later being moved thereby to a second work station. These two work stations are generally indicated in FIGURE 1 by the numerals 99 and 100.

Above the clamp 58 is arranged a longitudinal bar 102 having guides 103 receiving a rack bar 104. Adjacent one end and intermediate the ends of the member 102 are mounted shafts 106 about which is rotatable one end of a finger 107 biased by a spring 108 (FIGURE 2) to turn counterclockwise as viewed in FIGURE 3. An arm 109 is fixed to each shaft 106 and projects across the adjacent finger 107 to positively turn it in a clockwise direction in FIGURES 3 and 7 under conditions to be described. A stop 110 having an adjusting screw 111 is arranged to stop counterclockwise turning movement of the fingers 107 at the proper position. Each shaft 106 carries a pinion 114 (FIGURE 2) meshing with a second pinion 115 (FIGURES 3, 5 and 7), and the pinions 115 mesh with the rack 104.

The member 102 also is provided with two longitudinal slots 118 each slidably supporting a crosshead 119 in which is mounted a shaft 120 similar to the shaft 106. Each shaft 120 carries an assembly including fingers corresponding to the finger 107 and the finger 109, and the latter finger, as shown in FIGURES 3, 5 and 7, comprises an arm 122 having a plate 123 thereon spring pressed as at 124 to engage the leading edge of a book arranged between the fingers 107 and 122.

Each shaft 120 carries a pinion 125 directly meshing with the teeth of the rack 104. It will be apparent that the pinions 115 reverse rotation of the arms 107 relative to the arms 122 when the rack 104 is moved in either direction. The member 102 (FIGURE 2) is supported by brackets 130, and the assembly of elements just described is protected by a cover 131 shown only in FIGURE 2.

Referring to FIGURE 3, a shaft 135 is journaled in the member 102 adjacent one end thereof and carries a pinion 136 meshing with the rack 104. An arm 137, carried by the shaft 135, has its free end pivoted to a push rod 138, the lower end of which is provided with a band 139 in which rotates a cam 140 carried by the shaft 38. Rotation of the cam 140 rocks the arm 137 from the position shown in FIGURE 3 to a lower position to swing the fingers 107 and 122 to the operative positions shown in FIGURE 5.

Operation

With the apparatus running, an operator places a book in the proper position in front of the first pair of pushers 82 at the right hand end of the machine (FIGURE 1) with the edge of the book in which the openings are to be drilled at the lower or forward end thereof as viewed in FIGURE 6. The operation of the wheel 93 (FIGURE 1) moves the set of pushers referred to to the left, as viewed in FIGURE 1 and, propelled by the first pair of pushers 82 at the right hand end of the machine the book will move to the left in FIGURE 1. The lever 88 then retracts and the angle irons 83 and the second pair of pushers from the right will escape beneath the book and return to the position shown in FIGURE 1 ready for engagement with the adjacent edge of the previously fed book.

The book previously fed to the machine will be engaged by the second pair of pushers 82 from the right in FIGURE 1 to be moved to the first work station 99 whereupon the third pair of pushers 82 from the right will swing downwardly to escape beneath the book. After an operation is performed on the first book at the first work station 99, as described below, the retraction of the angle irons 83 will cause the third pair of pushers 82 from the right to engage the leading book to advance it to the second work station 100. This operation is repeated so long as the apparatus is running and is fed with books, the books with drilled openings being pushed to the left in FIGURE 1 from the second work station 100.

Each book is pushed to one of the work stations in the manner described and will be placed in approximately the correct position at each station. When such positions of the books are reached, the cam 140 operates the push rod 138 to rock the pinion 136 in a clockwise direction in FIGURE 3 to rotate the shafts 120 clockwise and the shafts 106 counterclockwise through the idler gears 115. Under such conditions the fingers 107 and 122 will swing to the operative positions shown in FIGURE 5 and movement of each finger 107 will be limited by its stop 111, the arm 109, if necessary, swinging slightly beyond its point of engagement with the adjacent edge of the arm 107. Each stop 111 positively accurately positions the trailing edge of the book at each work station. Each arm 122 will swing downwardly to engage the plate 123 with the leading edge of the book, such plate being able to give to the right in FIGURE 5 if necessary by virtue of its spring mounting.

After a book is in position for the drilling operations, the drills 79, normally inoperative, as shown in FIGURES 5 and 6, will be moved upwardly to perform the drilling

operations. These drills will be constantly rotated by the worm gearing 67, 77. At the proper time, the cams 45 will release the levers 48 from the lower ends of the rods 49, whereupon the springs 51 will move the clamp 58 downwardly into engagement with the book at each station to firmly hold the book in position. The cams 40 and 45 have their high and low points substantially opposite each other, so it will be apparent that the releasing of the clamp 58 will be followed by the moving of the motors 36 and associated elements to advance the drills from the positions shown in FIGURE 6 to the position shown in FIGURE 8, and accordingly, openings will be drilled through the book at each station.

Upon the completion of the drilling operations, the cams 40 and 45 will continue to rotate, the clamp 58 being lifted, and the motors 36 and drills 79 being retracted to their normal positions shown in FIGURE 6.

Upon completion of the drilling operations, reversal of the movement of the rack 104 will swing the fingers 107 and 122 to release the ends of the books, and the continued operation of the fingers 82 will advance each drilled book to the left of its position in FIGURE 1 and will supply a following book to the first work station 99.

In the punching of thinner books, it is possible to arrange the punches sufficiently close together to simultaneously punch all of the openings to receive the coil binder. Where a thicker book is to be so made, it is necessary to divide the book into two or more packs, with each partial pack separately punched, whereupon the previously separated parts of the book must be reassembled and this work is usually not wholly accurately done with the result that holes punched in separated sections of the book are not exactly in alignment. The present apparatus provides for the making of the holes through thicker books without the necessity of having to separate them in parts.

Since the present construction involves elements not present in punches, for example, the drills, drill mountings and drive gears therefor, it is impossible to arrange the centers a distance apart equal to the distance between the openings in the finished book. Therefore, the drills of each set are arranged apart a distance equal to twice the distance of the openings desired in the finished book. Upon the completion of the first drilling operation at the work station 99, the book is advanced to the second work station 100, at which point the positioning fingers 107 and 122 associated with the second work stage, that is, the right hand stage in FIGURE 3, will position the book accurately so that the drills will be aligned centrally of the spaces between the previously drilled openings. At the completion of the second stage of operation, therefore, the entire book thickness will be provided with openings spaced apart the proper distance to receive the spiral binder.

The combination of elements is such that it materially speeds up the operation of drilling the openings. The end result is that once the leading book has been drilled at the second work station 100, each succeeding operation of the apparatus turns out a completely drilled book. In other words, while the final drilling operation is being performed at the second work station 100, the first drilling operation is being simultaneously performed on a following book at the first work station 99. As stated, therefore, once the machine is in operation, each complete cycle of operation turns out and feeds from the left hand side of the apparatus in FIGURE 1 a completely drilled book ready for the spinning of the coil therein.

Thus, the present machine permits the rapid formation of openings through relatively thick books which cannot be done with punches due to the inability of the latter to punch through more than a minimum thickness of sheets. The present apparatus can perform its functions through relatively thick books and at the same time turn out a book ready for the coil binder upon each complete cycle of operation thereof. Conventionally, where thicker books

are turned out by the punching method, two or more punching operations are required, depending upon the thickness of the book and the separated parts must be reassembled. This greatly slows down the rate of production as distinguished from the present apparatus as stated above.

While two work stations and associated parts have been illustrated, it will be apparent that more than two such stations may be employed. In any case, the openings in the finished books will be arranged in a predetermined distance apart and the drills at each work station will be spaced apart a multiple of said predetermined distance, which multiple is equal to the number of sets of drills. Thus, if two sets of drills are employed, the multiple will be 2, the drills of each set being spaced twice said predetermined distance. If three sets of drills are employed, the multiple will be 3 corresponding to the number of sets of drills. The drills of each set will be so positioned that when the final drilling operation is completed, all of the book openings will be spaced apart the predetermined distance referred to.

It is to be understood that the form of the invention herewith shown and described is to be taken as a preferred example of the same and the various changes may be made as do not depart from the spirit of the invention and the scope of the appended claims.

I claim:

1. An apparatus for forming bookbinding coil receiving openings in books near one edge thereof and spaced a predetermined distance apart, comprising a plurality of spaced sets of aligned drills each comprising a work station, the drills of each set being spaced apart a distance which is a multiple of said predetermined distance corresponding to the number of said sets of drills, means for advancing books step-by-step to successive work stations, means for positioning a book at each work station as it reaches such station, comprising elements at each work station normally out of the path of travel of books being moved to and between said stations, and means operative after a book reaches each station for moving said elements into engagement with opposite edge portions of the adjacent book to position it accurately relative to the drills of the associated station, and means for moving all of said drills simultaneously to drill openings at all of said stations, the drills of each station being so positioned that at the final station, all of the openings will be drilled and all will be spaced said predetermined distance.

2. An apparatus for forming bookbinding coil receiving openings in books near one edge thereof and spaced a predetermined distance apart, comprising a plurality of spaced sets of aligned drills each comprising a work station, the drills of each set being spaced apart a distance which is a multiple of said predetermined distance corresponding to the number of said sets of drills, means for advancing books step-by-step to successive work stations, means for positioning a book at each work station as it reaches such station, comprising elements at each work station normally out of the path of travel of books being moved to and between said stations, means operative after

a book reaches each station for moving said elements into engagement with opposite edge portions of the adjacent book to position it accurately relative to the drills of the associated station, and means operative after said elements have engaged opposite edge portions of each book for clamping each book into position prior to movement of said drills to drill said openings, and means for moving all of said drills simultaneously to drill openings at all of said stations, the drills of each station being so positioned that at the final station, all of the openings will be drilled and all will be spaced said predetermined distance.

3. An apparatus for forming bookbinding coil receiving openings in books near one edge thereof and spaced apart a predetermined distance, comprising a pair of spaced sets of aligned drills respectively comprising a first and second work station, the drills of each set being

spaced apart a distance twice said predetermined distance, means for supporting books for movement through said work stations, comprising a plate slotted longitudinally of the direction of movement of the books, said advancing means comprising fingers projecting through said slots to engage the books, and means for reciprocating said fingers longitudinally of the slots of said plate, means engaging successive books placed on said supporting means ahead of said first work station for moving the books successively to said work stations, positioning means comprising elements parallel to the line of movement of books along said supporting means for positioning the books at each work station, means for engaging said elements with opposite edge portions of each book for positioning the books relative to the drills of each set, means operative after said elements have engaged each book for clamping such book against said supporting means, and means for moving all of said drills simultaneously to drill openings in books at both of said stations, the drills of said second station being positioned to drill openings equidistantly from openings previously drilled at said first station whereby all of the openings after operation of the drills of said second station will be spaced said predetermined distance.

4. An apparatus for forming bookbinding coil receiving openings in books near one edge thereof and spaced apart a predetermined distance, comprising a pair of spaced sets of aligned drills respectively comprising a first and second work station, the drills of each set being spaced apart a distance twice said predetermined distance, means for supporting books for movement through said work stations, means engaging successive books placed on said supporting means ahead of said first work station for moving the books successively to said work stations, positioning means comprising elements parallel to the line of movement of books along said supporting means for positioning the books at each work station, means for engaging said elements with opposite edge portions of each book for positioning the books relative to the drills of each set, means operative after said elements have engaged each book for clamping such book against said supporting means, and means for moving all of said drills simultaneously to drill openings in books at both of said stations, the drills of said second station being positioned to drill openings equidistantly from openings previously drilled at said first station whereby all of the openings after operation of the drills of said second station will be spaced said predetermined distance, said elements of said

positioning means comprising pivoted fingers arranged at each station and normally positioned out of the path of travel of the books, and means synchronizing movement of said reciprocating means and said fingers for swinging said fingers into engagement with the books at the respective stations after a book reaches each work station.

5. An apparatus for forming bookbinding coil receiving openings in books near one edge thereof and spaced apart a predetermined distance, comprising a pair of spaced sets of aligned drills respectively comprising a first and second work station, the drills of each set being spaced apart a distance twice said predetermined distance, means for supporting books for movement through said work stations, means engaging successive books placed on said supporting means ahead of said first work station for moving the books successively to said work stations, positioning means comprising elements parallel to the line of movement of books along said supporting means for positioning the books at each work station, means for engaging said elements with opposite edge portions of each book for positioning the books relative to the drills of each set, means operative after said elements have engaged each book for clamping such book against said supporting means, means for moving all of said drills simultaneously to drill openings in books at both of said stations, the drills of said second station being positioned to drill openings equidistantly from openings previously drilled at said first station whereby all of the openings after operation of the drills of said second station will be spaced said predetermined distances, a power driven cam shaft, and two sets of cams carried by said cam shaft, one of said sets of cams being connected to said clamping means to actuate it, the cams of the other set being connected to move said drills to drill the books after said clamping means has been rendered operative by said first named set of cams.
